US00D517982S

(12) **United States Design Patent** (10) **Patent No.:** **US D517,982 S**
Rad et al. (45) **Date of Patent:** **** Mar. 28, 2006**

(54) **PORTABLE BATTERY**

(75) Inventors: **Rodney Rad**, Los Angeles, CA (US);
Thomas Philip Henley, Los Angeles, CA (US)

(73) Assignee: **Compact Power Systems, Inc.**,
Woodland Hills, CA (US)

(**) Term: **14 Years**

(21) Appl. No.: **29/234,438**

(22) Filed: **Jul. 19, 2005**

(51) LOC (8) Cl. **13-02**

(52) U.S. Cl. **D13/103**

(58) Field of Classification Search D13/102-106,
D13/110, 118-119, 184; 429/96-100, 163,
429/176

See application file for complete search history.

(57) **CLAIM**

The ornamental design for a portable battery, as shown and described.

DESCRIPTION

FIG. 1 is a perspective view of a battery showing the new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.
